WASHING MACHINE

John Fisher Ross, Toronto, Ontario, Canada

Application July 31, 1939, Serial No. 287,445

4 Claims. (Cl. 68—151)

My invention relates to improvements in washing machines, and the object of the invention is to devise a simple, cheap, efficient machine which will provide for a continuous and thorough circulation of the water through the clothes and which will produce such circulation at lower speeds of rotation and in such a way that the clothes will not clog the machine to prevent quick and free circulation of the water, and further to provide means for preventing the forcing off of the lid of the washer by the accumulation of suds and the consequent spilling of the suds over the edge of the washer onto the floor, and it consists essentially of the arrangement and construction of the parts hereafter described.

Fig. 1 is a perspective view of my washing machine broken away to exhibit the interior structure thereof.

Fig. 2 is a vertical sectional view through my machine.

Fig. 3 is a plan view of my machine partially broken away to exhibit the interior construction.

Fig. 4 is a sectional plan view on line 4—4 of Fig. 2.

Fig. 5 is a sectional detail of the means for returning the suds at the edge of the washer towards the centre of the washer.

In the drawings like letters of reference indicate corresponding parts in the different views.

The numeral 1 indicates a water container mounted on a suitable stand. The upper edge of the water container wall is provided with an annular edge groove 1^x in which fits flange 5 of the lid 6.

7 is the driving shaft mounted in a bearing sleeve 8 extending through a circular opening 9 formed in the centre of the water container 1 and provided with a flange 10 formed integral therewith and bearing against the inner face of the bottom wall of the water container. 11 is a nut which is screwed onto the lower end of the sleeve 8 against the lower face of the bottom of the water container so that such bottom is clamped between the flange 10 and nut 11 to form a water tight joint.

A clothes container 12 located centrally within the water container 1 is provided with walls having perforations 12^x and 12° in the sides and bottom to allow of the passage of the water between the containers 12 and 1. The walls of the container 12 are spaced from the walls of the container 1 so as to allow for an intervening water space. The bottom of the clothes container 12 is provided with a central orifice 13.

14 is an outer bearing sleeve fitting around the inner sleeve 8 so as to revolve freely thereon. The sleeve 14 extends at its lower end through the orifice 13 in the clothes container bottom and is provided with an annular flange 15 secured to the plate 16 spaced below the clothes container bottom. A cap 16^x is secured within the sleeve 14 and to the shaft 7 so that the shaft 7, sleeve 14, and clothes container 12 revolve in unison around the sleeve 8. A thrust bearing 17 is interposed between the cap 16^x and sleeve 8, the sleeve 8 being provided with bushings 18 and 19 within which the shaft 7 revolves.

The upper rim of the container 12 is provided with an annular inwardly extending flange 23. 15 25 are radial impeller flanges located between the bottom of the container 12 and the plate 16 by which the water is drawn through the perforations 12° and impelled radially outward and then upward between the containers 12 and 1. 20

24 is an annular plate provided with depending annular flanges 26 and 27, the flange 27 being supported on an annular shoulder 1° formed in the interior of the water container 1. The plate 24 extends over the flange 23 and is spaced 25 upwardly therefrom. The flange 26 depends from the ring 24 so as to extend below the upper level of the flange 23 as clearly shown in Fig. 2 and is spaced inwardly from such flange so as to form space for the downward passage of the 30 water as it is carried over the flange 23.

Supported by the plate 24 and extending between the flanges 26 and 27 are angle bars 28 forming radial vanes which direct the water as it ascends between the containers 1 and 12 inward over the upper edge of the container 12 formed by the flange 23.

In order to prevent the accumulation of suds in the top of the machine forcing the lid 8 upward and allowing the suds to spill 1 from openings 29 in the ring 24 directly over the vanes 28 and slits 30 at the top of the vertical walls of the angle bars 28.

As the soapy water is carried violently against the vertical walls of the bars 28 it is forced 40 through the slits 30 so as to pass rapidly transversely beneath the opening 29.

As the suds build up in the top of the machine they cover the openings 29 and the rapid passing of the water beneath the orifices produces 50 a suction which draws the overlying suds down through the orifices and into the flow of water impelled inward by the next adjacent vane towards the centre of the machine.

The water passing over the rim of the clothes 55

5 container formed by the flange 23 radially off the bars 28 strikes the flange 26 and passes downwardly into the water in the clothes container and to the bottom perforations 12°, some of the water, during such downward travel, passing radially through the perforations 12^x to join the upwardly circulating water.

10 31 are ribs fitting the lower interior corner of the clothes container and serve to carry the water and clothes around with the container as soon as it starts to revolve serving to spread the clothes out radially and prevent them packing against the perforated walls.

15 By my arrangement the blades 25 circulate the water without the clothes container being rotated at high speed. The clothes container being rotated at lower speed, the clothes are not forced outward with great pressure against the perforated wall of the container and are carried freely around by the ribs 31 so as to ensure of the free circulation of water through the perforations 12^x.

20 Also as the suds build up in the top of the container such suds around the edge of the container are drawn down into the inwardly directed waterflow, thus preventing the suds building up to such an extent as to force their way outward between the container edge and its cover to spill on the floor.

25 What I claim as my invention is:

30 1. A washing machine comprising an outer stationary water container, an inner clothes container having a perforated bottom and rotatably mounted within the outer container to form an annular water space between the containers, 35 means for circulating the water passing through the bottom perforations of the clothes container radially outward and upward between the walls of the clothes and water containers, an annular plate carried by the water container and extending over the upper edge of the clothes container and spaced therefrom and having suitably spaced apart openings therein, an annular flange depending from the inner edge of the plate into the clothes container and spaced therefrom, angle bars carried by the plate and flange and extending radially beneath each opening and having a slit opening in the vertical wall thereof located at one side of the plate opening and against which the circulating water is carried by the rotating clothes container to be injected transversely of the plate opening.

45 2. A washing machine comprising an outer sta-

tionary water container, an inner clothes container having a perforated bottom and rotatably mounted within the outer container to form an annular water space between the containers, means for circulating the water passing through the bottom perforations of the clothes container radially outward and upward between the walls of the clothes and water containers, an annular deflecting plate carried by the water container and extending over the upper edge of the clothes container and spaced therefrom and having suitably spaced apart openings thereon, angle bars carried by the deflecting plate beneath each opening, the vertical wall of which extends at one side of the opening and having a horizontal slit opening therein at the top.

50 3. The combination with an outer stationary water container and an inner rotatable clothes container spaced therefrom, an annular horizontal plate carried by the water container to extend over the edge of the clothes container in spaced relation therewith and having orifices therein over which the gathering suds extend, a flange depending from the inner edge of the plate into the inner container, and means coacting with the rotating inner container for injecting a sheet of water transversely beneath the orifices to draw the overlying suds therethrough into the water flow.

4. The combination with an outer stationary water container and an inner rotatable clothes container spaced therefrom, an annular horizontal plate carried by the water container to extend over the edge of the clothes container in spaced relation therewith and having orifices therein over which the gathering suds extend, a flange depending from the inner edge of the plate into the inner container, and means coacting with the rotating inner container for injecting a sheet of water transversely beneath the orifices to draw the overlying suds therethrough into the water flow, such means comprising an angle bar vane, the vertical wall of which depends from the annular plate on the water approach side of each orifice, the vertical portion of the vane having a slit opening therein parallel with and adjacent to the annular plate, the horizontal portion of the vane extending from the lower edge of the vertical portion to the water receding side of the orifice.

50

JOHN FISHER ROSS.
